ELECTRICAL CONDUCTOR

William C. Robinson, Sewickley, and Ralph W. E. Moore, Mount Lebanon, Pa.; said Moore assignor to said Robinson

Application December 27, 1937, Serial No. 181,910

5 Claims. (Cl. 174—120)

This invention relates to electrical conductors of the types having an inner electrically insulated conductive structure and employing an outer protective jacket of fibrous material. Examples are rubber covered wire used as building wire or as the individual wires of various types of cable, such as flexible armored cable or non-metallic sheathed cable. Such jackets are usually coated with saturating and covering compounds. The present invention deals with the structure of the jacket rather than with the coating, which may be of any suitable sort. It is our purpose to provide electrical conductors of the insulated type which are fundamentally simple, and which are substantially equivalent in character to the present types of conductor assemblies which include braided or knitted coverings; which conductors are flexible, are securely and permanently organized, and which may be manufactured with a maximum of operating convenience and speed.

In manufacturing insulated conductors adapted when so desired to a moisture-resistant and/or flame-resistant treatment and adapted universally to use in cables or in housed or un-housed installation, it is necessary that the insulated conductor itself be adequately flexible and that the insulation surrounding the conductive element of the assembly be so organized that all its constituents remain in their initial arrangement in the assembly. Simplicity in the assembly both as to the number and arrangement of its constituent elements is a matter of primary importance, and the problem is to join this simplicity with manufacturing facility and permanence of organization.

In attaining our object a flexible conductive element, which may be either a single conductor wire, or a plurality of the same, is encased in a flexible, directly applied dielectric material, such as a rubber composition or a composition having electrical and physical qualities similar to those of rubber. The term "flexible" as herein applied to the conductive metallic element of the conductor is used in its common and non-technical sense, as meaning merely capability to be flexed. This flexible dielectric about the conductive element of the assembly is covered with a protective jacket in the form of a wrapping of thread, such for example as cotton, or paper, thread. Great manufacturing advantage is derived by applying this thread in the form of a simple helical wrapping called a serving rather than in the form of a braided or knitted fabric. When applied as a simple wrapping, however, the

turns of the wrapping tend to become separated, and to unwind and loosen when the conductor is flexed, due to deformation of the flexible dielectric. It has been proposed to hold the turns of a wrapping of this sort by means of threads inserted between the wrapping and the dielectric, or stitched under and over groups of turns of the wrapping. Aside from the manufacturing difficulties which such structure presents, it does not fully solve the problem of protecting the conductor in all directions of flexion against the tendency for turns or groups of turns to open up. It has been proposed also to hold the serving intact by means of saturating compounds and the adhesive effect of vulcanizing the rubber insulation by the heat of the saturating bath. While this has some effect, it is not sufficient to meet the requirements of working conditions under which a wire or cable must be bent severely and yet maintain its integral structure.

We have found that an improved outer protective jacket can be made by combining such a helical serving of thread, having its turns laid close together with a substantial lead and without overlap to form a closed wrapping or jacket giving substantially complete coverage, with an open locking structure of thread oppositely wound upon the jacket, the turns of thread in this locking structure being spaced apart to expose the greater part of the jacket.

This locking structure effectively prevents the serving threads from opening up when the conductor is bent, thus holding the serving intact. And although the locking structure lies outside the serving, the effect of the spacing of its turns is such that it brings about no material increase in the over-all diameter of the wire or cable. The effective diameter for practical purposes is fixed by the serving and whatever saturant or coating is applied to it, and is less than the diameter of a wire or cable similar in other respects but employing the usual braid. An outer jacket so formed is flexible, gives better coverage and consequent better protection than the conventional braid, is more rapidly applied and, when coated in the usual way, presents a good surface for printing and offers less resistance to being pulled when the wire or cable is fished into conduits or drawn through holes in beams and the like.

In the accompanying drawings, Fig. I is a view, chiefly in elevation but partly in longitudinal section, showing our conductor assembly as organized with a single locking thread. Fig. II is an elevational view showing our conductor

50

55

assembly organized with two locking threads. Fig. III is a view, taken in elevation, showing a conductor assembly in which a plurality of wrapping threads have been simultaneously wound with a simple helical lay.

In describing the insulated conductor of our invention, it should be explained that the simple conductor, such as is shown in the drawings forms one assembly in which our invention resides, and coherence and flexibility are the desired qualities of this conductor as such. Merely as shown, the conductor may, if so desired, be used in many electrical associations. The conductor as such may for some purposes, such as 10 for use in housing and conduits, or for use in armored cable, be provided with a coating of suitable moisture-repellent composition which is also desirably flame-resistant and many include a superficial wax finish as described in Patent 15 No. 1,635,829, the whole forming a flexible protective coating, the makeup of which is not a part of this invention. It may be used in making up non-metallic sheathed cable, or such as 20 the cable shown and described in Frederickson United States Patent No. 1,687,013, and may be used as the conductor in various other organizations. It is, therefore, the qualities of flexibility, 25 simplicity, and permanent organization in the fundamental structure shown, which are the results under consideration, without reference to added structure, or material, which may be associated with the conductor.

Referring to the drawing, in assembly the insulated conductor consists of a flexible conductive element 1, shown as a single conductor wire. The other core element of the assembly is a covering 2 of dielectric composition, such as rubber composition or a generally similar composition 30 directly surrounding the conductive element. Around the core of the assembly there is wound, with a simple helical lay, a wrapping 3, the turns of which are in contact with each other longitudinally of the core. This wrapping 3 is desirably laid with a number of individual 35 threads or "ends," as they are called, giving a substantial lead in order to increase the speed with which it may be applied to the core; and while it remains in the coherent condition shown, serves to confine and protect the flexible dielectric material of the core.

In order so to bind the turns of the wrapping that they are held against spreading by deformation of the flexible dielectric element when the conductor is flexed, we lock the turns of 55 wrapping thread in position by means of at least one locking thread 4 helically wound oppositely to the winding of the wrapping, to lie wholly outside the wrapping and to cross the turns of the wrapping thread while forming a 60 substantial angle with the longitudinal axis of the core. The angle formed with the longitudinal axis of the core by the locking thread should be substantial, to lessen likelihood that the thread may be broken under disruptive forces 65 exerted by the dielectric material of the assembly in flexion of the conductor. We prefer that the angle formed with the longitudinal axis of the conductor by the locking thread should not be substantially less than a 60° angle, having 70 found that an angle approximating 60° provides a maximum locking effect for the wrapping thread in all directions of flexion of the conductor, while resulting in minimizing breakage of locking thread when the conductor is subjected 75 to severe conditions of use.

In order to insure coherence of the conductor wrapping under all conditions of use, we find it desirable, although generally unnecessary, to employ one or more additional locking threads 5, all the locking threads being similarly wound upon the wrapping to form a reverse helix there-with. Irrespective of the number of locking threads included in the assembly, these threads should be so laid that each forms a substantial angle with the longitudinal axis of the conductor core, as in the case of a single locking thread, 10 and find that the optimum arrangement is similarly so to lay all the locking threads that they each form an angle of approximately 60° with the longitudinal axis of the conductor core. The 15 locking threads are throughout their turns spaced uniformly from each other, giving the effect of parallelism in their positioning.

Both the wrapping thread and the binding thread, or threads, may be rapidly laid upon the 20 core of the conductor, and are of such nature and arrangement that they do not unduly detract from the flexibility of the core structure of the conductor. In this connection we have found that as many as three or four locking 25 threads, spaced in what is effectively a position of parallelism with each other, are not detrimental from the viewpoint of flexibility. Desirably, the thread which forms the wrapping 3 is a fibre thread of moisture-absorbent character, 30 such as cotton, linen, hemp, or paper thread. For either the wrapping thread, or the locking thread, or threads, we have found that we may suitably employ thread of any material which has adequately high strength with respect to its 35 cross-section. By the word "thread" we mean to include coherent filaments of any suitable material as well as the tightly twisted fibrous structures comprising more than one strand, and which are commonly designated as "thread" or 40 "cord." Each turn of the locking "thread" may be multiple, that is, consist of two or more strands, and as so organized is to be considered to be a single thread.

Fig. III of the drawings shows a conductor assembly in which a plurality of wrapping threads 45 have been simultaneously applied. These threads, wound in multiple, have, however, a simple helical lay, corresponding to that shown in Figs. I and II. The one or more locking 50 threads 5 are identical with the locking threads 4 of Figs. I and II.

As compared with braided or knitted conductor structures, the wrapped and locked covering of our invention is at least equally flexible as 55 conductor assemblies made with braided or knitted coverings, and is of smaller diameter than a conductor assembly comprising a braided or knit covering. It is to be understood that, if desired, a double wrapping may be provided, with 60 the thread or threads of the outer wrapping arranged in a simple helical lay, with the turns lying side by side in the wrapping, and not in part crossing each other as in a braided or knit covering. In such arrangement locking thread, 65 or threads, are applied similarly to the outer wrappings. Such double wrapping is analogous to a double covering of braided or knitted fabric, and bears the same relation to it that the single locked wrapping shown and described bears to a 70 conductor comprising a single braided or knit covering. As explained above, our invention resides in the use of a layer of wrapping arranged in a simple helical lay, and with a locking thread, or threads, lying in an opposed helix 75

wholly outside that wrapping, irrespective of the omission or inclusion of other structure in the conductor assembly.

Our conductor has been subjected to relatively 5 severe tests, approved by underwriters, in order to prove its ability to meet the demands of service. One such test, which it successfully passed, is a bending test in which the conductor is flexed at least six times on a radius equal only to 1.5 10 times the external diameter of the conductor assembly. No locking thread was broken, nor turns of the wrapping thread opened under subjection to this test. The conductor similarly has passed the "kink" test. That test is to grasp 15 the conductor at two points separated a substantial distance from each other, and then to give the conductor a quick torsional twist. This done successively in both directions, so that the "kink," or localized projection from the normal 20 line of the conductor, is formed both with and counter to the direction in which the wrapping of the conductor is laid.

The proper use of the locking thread has also a bearing on a suitability of the conductor, which 25 is not immediately apparent. This indirect bearing is to increase the flame resistance of the conductor. Assuming that the organization herein specifically described is treated first with an inflammable asphalt composition, and has 30 outside the asphalt a flame-retardant coating, such as pitch, the flame-retardance is dependent upon the coherence of the outer coating. If the coating material of the conductor be softened by flame impingement thereon, its binding effect on 35 the wrapping of the conductor assembly is decreased. In the absence of a properly arranged locking thread, or threads, the turns of the wrapping thread open, and in so doing disrupt the coating material. This exposes the asphalt to 40 the flame, and results in destruction of the insulation in that region of the conductor. By the arrangement of the locking thread, or threads, in our conductor it has the same flame-retardant qualities as a similarly treated conductor 45 comprising a knit or braided fabric.

45 We claim as our invention:

1. An insulated conductor structure having a 50 flexible metallic conductive element, an inner insulating structure and an outer protective jacket in the form of a filamentary insulating serving 55 surrounding the said metallic conductive element with the turns of said serving lying against each other in a simple helical lay to form a closed wrapping, and a locking filament laid in a helix opposite in sense to the helix of the closed 60 wrapping and disposed in the assembly outside and in contact with the said wrapping, said locking filament being laid with its turns out of contact with each other in an open binder structure and arranged each to form an angle approximately as great as 65 65

70 70

2. An insulated conductor structure having a flexible metallic conductive element, an inner insulating structure and an outer protective jacket 65 in the form of a coherent filamentary insulating serving surrounding the said metallic conductive element with the turns of said serving lying against each other in a simple helical lay to form a closed wrapping, and a permanently in-

tegrant binder structure for the said wrapping consisting of a locking filament laid outside the closed wrapping with its turns out of contact with each other in a helix opposite in sense to the helix of the closed wrapping and forming a substantial angle with the longitudinal axis of the conductor, the said locking filament being in direct contact with the said closed wrapping positively to oppose and effectively to inhibit opening between the coherent wrapping turns 10 during flexion of the conductor.

3. An insulated conductor structure having a flexible metallic conductive element, an inner insulating structure and an outer protective jacket in the form of a coherent filamentary insulating serving surrounding the said metallic conductive element with the turns of said serving lying against each other in a simple helical lay to form a closed wrapping, and a locking filament permanently integrant for the said closed 15 wrapping laid in a helix opposite in sense to the helix of the closed wrapping and in position effectively to inhibit opening between coherent turns of the wrapping, said locking filament being laid with its turns out of contact with each 20 other in an open binder structure and arranged each to form an angle approximately as great as 60° with the longitudinal axis of the conductor.

4. An insulated conductor structure having a flexible metallic conductive element, an inner insulating structure and an outer protective jacket in the form of a coherent filamentary insulating serving surrounding the said metallic conductive element with the turns of said serving lying against each other in a simple helical lay to form 35 a closed wrapping, and a permanently integrant binder structure for the said closed wrapping consisting of a locking filament laid outside the closed wrapping in a helix opposite in sense to the helix of the closed wrapping and with its turns out of contact with each other, the position of the open binder structure in the assembly being such as positively to oppose and effectively to inhibit opening between the coherent wrapping turns during flexion of the conductor, and the 40 lead at which the locking filament is laid being so limited that the turns of the filament form with the longitudinal axis of the conductor an angle sufficiently great effectively to inhibit the tendency for the locking filament to break with loss of its locking effect on the turns of the 45 wrapping upon severe flexion of the conductor.

5. An electrical conductor assembly comprising an electrically insulated inner conductive structure and an outer protective jacket therefor in the form of a helical serving of fibrous thread, having its turns laid close together with a substantial lead and without overlap to give substantially complete coverage, in combination with an open locking structure of thread oppositely wound upon the jacket at a substantial angle with the conductor axis and with its turns so spaced as to expose the greater part of said jacket, whereby the jacket is held intact despite bending of the conductor assembly and the overall diameter fixed by the jacket is not materially increased by the locking structure.
